US0D1054641S

(12) **United States Design Patent** (10) **Patent No.:** **US D1,054,641 S**
(45) **Date of Patent:** **** Dec. 17, 2024**

(54) **CLEANING ROBOT**

(71) Applicant: **SHENZHEN PUDU TECHNOLOGY CO., LTD.**, Guangdong (CN)

(72) Inventors: **Zhiwei Qin**, Guangdong (CN); **Simin Huang**, Guangdong (CN)

(73) Assignee: **SHENZHEN PUDU TECHNOLOGY CO., LTD.**, Guangdong (CN)

(**) Term: **15 Years**

(21) Appl. No.: **29/844,717**

(22) Filed: **Jun. 30, 2022**

(30) **Foreign Application Priority Data**

Dec. 30, 2021 (CN) 202130877730.0

(51) **LOC (14) Cl.** **15-05**

(52) **U.S. Cl.** **D32/21; D15/199**

(57) **CLAIM**

The ornamental design for a cleaning robot, as shown and described.

DESCRIPTION

FIG. 1 is a top, front, right side perspective view of a cleaning robot, showing our new design;
FIG. 2 is a top, rear, right side perspective view thereof;
FIG. 3 is a front elevation view thereof;
FIG. 4 is a rear elevation view thereof;
FIG. 5 is a left side elevation view thereof;
FIG. 6 is a right side elevation view thereof;
FIG. 7 is a top plan view thereof; and,
FIG. 8 is a bottom plan view thereof.

The broken lines are included to show features that form no part of the claimed design.

1 Claim, 8 Drawing Sheets
